ROAD FORM OR RAIL

Filed Aug. 18, 1927

FIG. 1.

UNITED STATES PATENT OFFICE.

GEORGE H. MILLER, OF MILWAUKEE, WISCONSIN, ASSIGNOR TO METAL FORMS CORPORATION, OF MILWAUKEE, WISCONSIN, A CORPORATION.

ROAD FORM OR RAIL

Application filed August 18, 1927. Serial No. 213,887.

In the construction of concrete roads, rails or forms are usually laid along the edges of the subgrade to act as a form for the concrete, as well as rails upon which a finishing machine may ride. It is obviously of primary importance to fasten these rails or forms to the ground in a very rigid and positive manner. It is universally the custom to employ stakes to do this, stake boxes having openings therein being utilized in conjunction with openings in the rails or forms to receive the stakes. Heretofore the stake boxes and rails or forms have been of a unitary construction. The assembling of the boxes has always been dependent on the rail or forms. The making of these boxes is complicated by the necessity of attaching them to the rails before they are completely assembled.

This invention has for its primary object to provide a stake box for rails or forms that is completely assembled before it is attached to the rail or form. Such a box supplies a long felt need in the art, as it naturally facilitates the assembling of the rail or forms with the stake boxes, as well as simplifying the manufacture of the boxes.

In carrying out the invention a stake box of distinctly new design is provided, together with novel means for attaching it to a rail or form. In the form of the invention embodied herein this means comprises studs, having enlarged heads, which are fastened to the box. These studs are adapted to engage with openings of keyhole formation in the rail or form whereby the box is securely attached thereto.

This invention is further characterized by providing means for preventing disengagement of the studs from the openings in the rail. To attain this end means are supplied for fastening the bottom portion of the box to the rail, thereby preventing any upward movement of the box which would cause the studs to disengage from the openings.

With these and further objects in view, as will in part be hereinafter stated and in part become apparent, the invention comprises certain novel constructions, combina-

tions and arrangements of parts as subsequently specified and claimed.

For a complete understanding of the invention reference may be had to the following description and accompanying drawings, in which:

Figure 1 is a perspective of the new stake box applied to a road rail.

Figure 2 is a side view taken with the rail shown in cross section.

Figure 3 is a fragmentary showing of the inner face of one side of the rail, illustrating the openings therein by which the box is attached.

Figure 4 is an enlarged detail sectional view on line 4—4 of Figure 1.

While the preferred form of the invention is herein set forth, it is to be clearly understood that it is not to be limited to the exact construction set forth, because various changes and modifications of these details may be provided in putting the invention into practice within the scope of the appended claims.

A rail or form 1 which is adapted to be laid along the edges of a subgrade and acts as a form for the concrete, as well as the support upon which a finishing machine may ride, comprises inner and outer side members 2 and 3. These members are connected on the top of the curved portion 4, which is the riding surface of the rail. The lower end of the side 3 terminates in a flange 5. This flange is securely fastened to a flange 6 integral with the inner side. The openings 7 extend through both of the flanges 5 and 6 and are adapted to have stakes pass therethrough. Any suitable means may be used in connecting the flanges 5 and 6. A particular feature of this invention is, however, that the same means which attaches the bottom of the box to the rail also fastens these two flanges together.

To provide for attachment of a box thereto openings 8, of keyhole formation, are provided in the rail. As shown in the drawings these openings are larger at the top than at the bottom. In the present form three of these openings are shown, although any number found suitable may be utilized.

A stake box made in accordance with this invention comprises a body 9, of arch-shape formation, having the sides 10 integrally connected by the top 11. One edge of each of the side members is inclined to conform with the inclination of the side 3 of the rail. These inclined sides of the box terminate in flanges 12 integral therewith, as does the top having the flange 13. Studs 14, 10 of the construction shown in Figure 4, are fastened to these flanges 12 and 13, one bolt being attached to each flange. These studs are rigidly held on the flanges by being riveted thereto.

15 To attach the box to a rail or form, the heads of the studs are passed through the larger portion of the openings after which the box is forced downward. It will be noted that in the last mentioned position 20 the heads of the studs will not pass through the reduced portion of the openings, whereby the box is securely attached to the rail.

To prevent any upward movement of the box, which would cause disengagement of 25 the studs from the openings, the box is attached to the flange 5 in the following manner; the bottom of the sides of the box terminate in flanges 15, integral therewith. These flanges have the openings 16 which 30 coincide with the smaller openings in the flanges of the rail. Bolts or rivets are passed through these openings to securely fasten the various flanges together. It will be noted that after the flanges 15, 5 and 6 35 have been fastened together, prevention of any upward movement of the box is obtained, as well as a rigid construction of the rail, no other means for holding the flanges of the rail together being necessary.

40 The opening 17 in the top of the box is adapted to have a stake pass therethrough. The stake passing through this opening and the opening 7 in the rail securely holds the rail or form to the ground. To acquire a 45 rigid relation between the stake and the box elongated openings 18 are provided in the top portion of the sides of the box. These openings accommodate a wedge which bears against the stake and the sides of the openings, whereby the desired rigidity is obtained.

By assembling these boxes in their 55 entirety before they are attached to the rails the manufacture thereof is greatly facilitated. A very positive connection with the rail is also afforded. It will be noted that the rails or forms and boxes may be shipped 60 separately, in which condition they may be readily packed in a very small space. By placing the keyhole openings at different places along the rail or form variability in the position of the stake boxes may be obtained, as desired.

Having thus described my invention, 65 what I claim as new, and desire to secure

by Letters Patent of the United States is:

1. The combination, with a road rail or form, having openings therein of keyhole formation, of a stake box, said box including flanges having studs fixed thereto, said 70 studs entering the openings in the rail or form to fasten the box thereto.

2. The combination, with a road rail or form, having openings therein of keyhole formation, of a stake box, said box including side and bottom flanges adapted to bear 75 against the rail or form, studs fixed to the flanges entering the openings in the rail or form, and means fastening the bottom flanges of the box to the rail or form.

3. The combination, with a road rail or form, having openings therein of keyhole formation, of a stake box, said stake box including inclined side flanges and bottom flanges, studs having enlarged heads fixed to 85 the side flanges entering the openings in the rail or form, and means fastening the bottom flanges of the rail, whereby upward movement of the box is prevented.

4. As an article of manufacture, a stake 90 box for road rails or forms comprising a body portion having side and bottom flanges, studs having enlarged heads fixed to the side flanges for securing said flanges to a road rail after the stake box has been 95 completely assembled.

5. As an article of manufacture a stake 100 box for road rails or forms comprising a body portion having side and bottom flanges, studs fixed to the side flanges whereby the box may be attached to a road rail or form, and means on the bottom flange for preventing upward movement of the stake box after it has been attached to a rail or form.

In testimony whereof I affix my signature.
GEORGE H. MILLER.
